UNITED STATES PATENT OFFICE

JOHN ALLEN HEANY, OF NEW HAVEN, CONNECTICUT, ASSIGNOR TO SIRIAN LAMP COMPANY, OF NEWARK, NEW JERSEY, A CORPORATION OF DELAWARE

INCANDESCENT ELECTRIC LAMP

Application filed July 3, 1916, Serial No. 107,367. Renewed April 18, 1924.

This invention relates to incandescent electric lamps and has for its object to provide an improved lamp which is highly efficient and has an unusually long life. This is accomplished by constructing the glower in the novel manner hereinafter described, and by causing the glower to operate in an inert gaseous medium, such as nitrogen, or the like.

According to the present invention, the glower is made relatively short, but of unusually large diameter for the purpose of reducing the convection losses. However, in making the glower of sufficient diameter to reduce the convection losses, the strength of the glower and the necessary resistivity to produce the proper degree of incandescence are not sacrificed, for, as will hereinafter appear, the glower is so constructed that it possesses great strength at the operating temperature and is capable of reaching a high degree of incandescence, even in the small size lamps and on relatively low voltages.

In its preferred form, the glower comprises a resistor, preferably of tungsten, or tungsten alloy, and a support preferably composed of a highly refractory material, such as a rare oxide, or a mixture of rare oxides which possess great strength at the operating temperature. The resistor is so associated with the support that the former heats the latter to incandescence. As will hereinafter appear, the resistor may also act as the radiating surface and may, therefore, be in the nature of a helical coil wound upon the support, or the resistor proper may be embedded in the support, and an additional radiating surface may be provided, preferably composed of tungsten or tungsten alloy, so that in either instance, the radiating surface is composed of tungsten or a tungsten alloy. In any case, the support of refractory compound, together with the resistor and the additional radiating surface, when one is employed, are so associated as to form a glower which is relatively short, but of unusually large diameter to reduce the convection losses. It has been proved in practice that the convection losses from glowers of small diameter are much greater proportionally than from glowers of large diameter, and it is for this reason that the glower, in ac-

cordance with the present invention, is given the size and shape herein disclosed. The convection losses are also dependent to some extent upon the nature of the medium in which the glower operates and in order to further increase the efficiency and life of the lamp, the glower is made to operate in an inert gaseous medium of low thermal conductivity, such as nitrogen, mercury vapor, helium, or argon. Furthermore, as the present lamp may be operated at higher temperatures than heretofore contemplated, it is essential for this reason also that the glower operate in an inert gaseous medium to reduce evaporation of the glower.

The invention is illustrated in the accompanying drawing, in which:—

Fig. 1 is a front elevation of the improved lamp; and

Figs. 2 to 5, inclusive, are vertical longitudinal sections of four different forms of the glower.

Referring first to Fig. 1, it will be seen that the lamp comprises the usual glass bulb 1, which may be made of any suitable shape. The threaded metallic base 2 is associated with the bulb 1 in the usual manner, and is electrically connected to the two lead wires 3 and 4. The glower proper is shown at A and is supported in the bulb 1 by means of the wires 3 and 4, in any suitable manner which will tend to reduce the conduction losses through the lead wires.

The detailed construction of the glower A is illustrated in Figs. 2 to 5, inclusive. In the form of the glower shown in Fig. 2, a support *a* is employed upon which is wound the resistor coil *b*. As above stated, the resistor *b* is preferably made of tungsten or tungsten alloy and the support *a* is preferably made of any refractory material of low conductivity and which is capable of being effectively heated to incandescence by means of the tungsten resistor. Preferably, the support *a* is made of a rare oxide or a mixture of rare oxides, such as thoria, zirconia, magnesia, or the like. It is obvious that any one of these oxides may be used by itself, several may be used in a mixture, or one or more may be mixed with a refractory

metal, such as tungsten. Preferably, however, the support is made of thorium oxide.

The coil of tungsten wire b is wound upon the support a with the coils positioned as closely as possible without short-circuiting. It will be noted that in this form of the glower, the tungsten coil acts not only as a resistor to heat the support a to incandescence, but also acts as the radiating surface. 10 It may be desirable, in some instances, to provide a radiating surface which is separate and distinct from the resistor proper. This may be accomplished as shown in Fig. 3 by providing the tungsten coil with two layers, 15 the inner layer b^1 of which is embedded in the refractory support a' , and the outer layer b^2 of which is at least partly exposed. These two layers of coils are connected in series so that the current traverses both layers of coils, 20 but the inner layer b^1 being embedded in the support of refractory compound, serves as a resistor to heat the support and the exposed surfaces of the outer layer of coils b^2 constitute the radiating surface for the glower.

25 In the modification of Fig. 4, the tungsten coil b' , or the resistor, is completely embedded in the support a'' . The radiating surface is formed by applying to the support a'' , a coating c of tungsten, carbon or similar material 30 which radiates a large amount of energy per unit of surface area at a given temperature.

In Fig. 5, the glower is constructed somewhat similar to the glower shown in Fig. 4, except that the resistor coil of tungsten is 35 formed in a different manner. In this form of the glower, the support a''' is similar to the support shown in Fig. 4, except that it is provided with a helical groove d which is filled with tungsten or a tungsten alloy to 40 produce in effect a coil b'' . The current in traversing the successive turns of tungsten lying in the helical groove d heats the support a''' to incandescence. A radiating surface c which may be similar in all respects to the 45 radiating surface shown in Fig. 4 may be applied to the support, so that the operation of the glower illustrated in Fig. 5 is substantially identical with that shown in Fig. 4.

It will now be noted that in all of the forms 50 of the glower herein disclosed, a resistor is employed, preferably made of tungsten or a tungsten alloy. The lamp may, therefore, be operated at very high temperatures. It is 55 a well recognized fact that the higher the temperature at which a lamp is operated, the greater will be the efficiency of the lamp. This high temperature at which the lamp is operated and the large diameter of the glower 60 do not, however, tend to detrimentally affect the glower, for the support of refractory compound possesses great strength at the operating temperature. The glower is, therefore, 65 not only immune to damage when the lamp is not burning, but may be safely operated at

high temperatures without danger of injury to the glower.

As above stated, the glower is operated in an inert gaseous medium, such as, nitrogen, mercury vapor, helium, argon, or any gas 70 which has low thermal conductivity to assist in reducing convection losses and which will prevent to as great an extent as possible, evaporation of the glower, even at the high temperatures at which the glower is capable 75 of operating.

It has heretofore been attempted to reduce the convection losses by the use of a coiled filament of relatively large diameter, but the diameter of the coil could not be made as 80 large as desirable to materially decrease the convection losses without materially weakening the strength of the filament. Furthermore, in such a type of lamp, the relatively large and hence weak filament coil prohibited 85 operation of the lamp at high temperatures. In the present instance, the entire glower is of sufficient diameter to materially decrease the convection losses and the strength of the glower instead of being decreased by being 90 made large in diameter is materially increased. The diameter of the glower is not limited by strength, and, therefore, any diameter which will allow of the specified 95 wattage from the consequent surface may be used.

All of the forms of the glower herein disclosed have a radiating surface composed of a material which will radiate a large amount of energy per unit of surface area 100 at a given temperature. The resistor in each of the glowers herein disclosed, whether the same be embedded in the support as in Figs. 3, 4 and 5, or surrounding the support as in Fig. 2, being made of tungsten or tungsten 105 alloy has a high specific resistance at the operating temperature, has a high melting point, and a very low vapor density at the operating temperature. The support being made of one or more rare oxides or a mixture of the same with tungsten or other refractory metal possesses great strength at the 110 operating temperature.

It will now be seen that by constructing the glower in the manner described above, it 115 may be made relatively short and of unusually large diameter, thereby not only decreasing the convection losses, but insuring durability and strength, even at the highest operating temperatures. The composition of 120 the glower permits it to be made of large diameter without reducing its resistance below that required for a high degree of incandescence. The atmosphere of inert gas in which the glower operates materially assists in bringing about the results striven for in making the glower in the novel manner described, and, therefore, the specific construction of the glower and the medium in which it operates are both responsible for the 125 130

marked results produced by the present lamp.

It is obvious that the glower may be constructed in various other different ways without departing from the scope of the invention, as defined in the following claims.

What I claim is:—

1. A glower for incandescent electric lamps comprising a resistor containing tungsten, a support of refractory compound in intimate contact with the resistor and capable of being heated to incandescence thereby, and a radiating surface associated with the glower composed of tungsten.
- 15 2. A glower for incandescent electric lamps comprising a support of refractory compound and a coil of tungsten wound upon said support, said coil having an inner layer of turns embedded in the refractory compound to act as a heater, and an outer layer of turns which are at least partly exposed to act as a radiating surface.
- 20 3. An illuminant for incandescent electric lamps, comprising a relatively short large-diameter body of refractory material, a radiating element of highly refractory metal encompassing said body, and a resistor coil embedded in said body and in series therewith.
- 25 4. An illuminant for incandescent electric lamps, comprising a relatively short large-diameter body of refractory material, a radiating coil of tungsten containing metal encompassing said body, and a resistor coil embedded in said body and in series electrically with said radiating coil.

In testimony whereof I affix my signature.
JOHN ALLEN HEANY.
